Primary Examiner — Ricky Pham(74) *Attorney, Agent, or Firm* — Luedeka Neely Group, PC(57) **CLAIM**

The ornamental design of an electric rice cooker and warmer, as shown and described.

DESCRIPTION

FIG. 1 is perspective view of the electric rice cooker and warmer of my new design;

FIG. 2 is a front elevational view of the electric rice cooker and warmer of my new design;

FIG. 3 is a rear elevational view of the electric rice cooker and warmer of my new design;

FIG. 4 is a right side view of the electric rice cooker and warmer of my new design;

FIG. 5 is a left side view of the electric rice cooker and warmer of my new design;

FIG. 6 is a top plan view of the electric rice cooker and warmer of my new design; and,

FIG. 7 is a bottom plan view of the electric rice cooker and warmer of my new design.
